SIGNALING SYSTEM FOR RAILROADS

Charles S. Bushnell, Rochester, N. Y., assignor
to General Railway Signal Company, Rochester, N. Y.

Application December 30, 1932, Serial No. 649,612

15 Claims. (Cl. 246—45)

This invention relates to automatic block signaling systems for railroads and more particularly to a system having a plurality of signal indications governed according to the character of energy present in the track circuit of each block, as distinguished from a system using line wires between blocks.

In one well known type of automatic block signaling system, the signals are arranged to display a stop or most restrictive indication when a train occupies the associated block, and line circuits are employed to reflect this condition back to effect the display of successively lesser restrictive indications at signals located one or more blocks in the rear. Such line circuits are not only costly to construct and maintain but also any failure of these circuits due to broken line wires or crosses between wires will obviously result in improper operation of the signals. Also in such systems, these line circuits are often extended parallel to or in a cable with power transmission circuits, and consequently it has been found that the signal line circuits may be falsely energized from current either induced or conducted from the power transmission wires which obviously results in an improper signal indication. The track circuit for effecting the display of a stop or most restrictive indication at its associated signal is usually of the normally energized type employing a track relay which requires a comparatively low resistance shunt to effect the dropping of its contacts because the characteristics of these relays are such that the current required to effect the dropping of the contacts is of a substantially lesser amount than the current required to pick up the contacts.

In view of the above and other considerations, it is proposed in accordance with the present invention to construct an automatic block signaling system having track circuits which are energized by impulses of a polarity and arrangement selected by forward traffic conditions to form distinctive codes, and it is proposed to provide means distinctively responsive to each of these codes in a manner to effect the display of a corresponding signal indication. It is further proposed to increase the reliability of the track circuits governing the display of a stop signal indication by causing such an indication to depend upon the picking up of an associated track relay rather than upon its dropping away.

Other objects, purposes and characteristic features of the present invention will appear as the description therefor progresses, during which references will be made to the accompanying draw-

ings which show the invention in a manner to make it easily understood, rather than with the idea of showing the particular construction preferably employed in practice, and in which:—

Fig. 1 diagrammatically shows an automatic block signaling system arranged in accordance with the present invention for governing traffic in a single direction over a portion of a railway system.

Fig. 2 shows a modified form of a block signaling system also in accordance with the present invention.

Referring to Fig. 1 of the accompanying drawings, a portion of a railway system has been shown as divided into blocks or insulated track sections T^1 , T^2 , T^3 and T^4 , and although the signaling apparatus and circuits associated with each of these blocks is substantially identical, it is considered expedient to duplicate this apparatus and circuits at each location in order to disclose the manner in which the system functions to display each indication as transmitted successively to the rear of an occupied block. Inasmuch as identical apparatus is employed at each block, like reference characters will be given to the like apparatus and distinctive exponents will be assigned thereto by which they may be associated with their proper location in the system.

A three-position polarized track relay TR (with distinctive exponent) is connected across the rails of each block in the conventional manner, and these relays may be of any suitable type such as the type disclosed in the patent to O. S. Field No. 1,749,331 granted March 4, 1930. A normal slow releasing neutral relay NR (with distinctive exponent), and a reverse slow releasing neutral relay RR (with distinctive exponent) are employed to repeat the relative energized positions of these track relays. The other end of each track section, that is, the end opposite the track relays TR , is energized through contacts of an impulsing relay P (with distinctive exponent) from a suitable source of energy B (with distinctive exponent) which may be a storage cell such as conventionally used in track circuits. This relay P is illustrated as being of the type disclosed in the prior application of O. S. Field Ser. No. 452,666 dated May 15, 1930, and it may be here mentioned that this relay when energized operates an armature about a center pivot point in equally time-spaced oscillations to periodically and alternately open and close electrical circuits. It is however desired to be understood that the present system is not limited

to the use of such a relay as other arrangements may be substituted, such as two neutral relays having their energizing circuits interlocked to produce alternate operation.

5 A signal S (with distinctive preceding numeral) is shown as governing traffic in a single direction over each of the above mentioned track sections T (with distinctive exponents), and although these signals have been illustrated as being of 10 the individual color light type, it is understood that any other type of signal may be employed and controlled in a manner obvious from the following description. A control circuit for each 15 signal light of the signals S is shown in detail, and it is understood these are the lights or the incandescent lamps associated with the corresponding unit of the signals S shown at the entrance of each block or track section. The upper 20 lights G, Y and R (with distinctive preceding characters by which they may be associated with the corresponding signal S) may be the conventional three indication signal while the lower 25 lights AG and AR (also having distinctive preceding characters) are employed to modify or determine the degree of restriction of the upper caution signal light Y, but the lower red light AR is always displayed in combination with either the upper green light G or the upper red light R. In this arrangement the four signal 30 aspects may be arranged in their relative degrees of restriction as a green over a red light for a proceed indication, a yellow over a green light for a proceed-caution indication, a yellow over a red light for a restricted caution indication, 35 and a red over a red light for a stop indication.

Having thus described the various apparatus associated with Fig. 1, it is believed that the function of the system to display the various signal indications will be more readily understood by 40 assuming a particular traffic condition and describing the operation of the apparatus resulting therefrom, or that is, it will be considered that a train represented by the symbol A is occupying the track section T¹.

45 The train A is then effective to shunt the track circuit current from the track relay TR¹ thereby causing its contact 4 to assume a de-energized position as shown, which in turn is effective to de-energize the slow acting relays RR¹ and NR¹. 50 A stop indication is then displayed at the signal 1S by energizing the red signal lamp 1SR over a circuit including back contact 5 of relay NR¹ and back contact 6 of relay RR¹, and the red signal lamp 1SAR is also energized over a circuit 55 including back contact 7 of relay NR¹ and back contact 8 of relay RR¹.

It was previously mentioned that the impulsive relay P will continuously operate in the form shown in Fig. 1 in equally time-spaced oscillations, which operation may be briefly described by referring to relay P¹, which relay, when in the condition shown, has a circuit completed for energizing its right hand operating coil from (+), over wire 9, through its right hand operating coil, wires 10 and 11, through its contact 12 in the position shown, and wire 13 to (-). This circuit is then obviously effective by shunting the left hand coil to cause the right hand coil to operate the armature 12 to its dotted position, 70 which then obviously shunts the right hand coil and causes the left hand coil to attract the armature 12 back to the position shown. This operation continues to cause periodic and alternate oscillations of the contacts operated by the 75 relays P. It may also be mentioned that the

contacts of the relays P are so arranged that during operation any particular set of contacts is being closed at substantially the same time as the opposite set of contacts is being broken, or in other words, a negligible period of time exists 5 in which neither set of contacts is closed.

With the impulsive relay P¹ in the position shown the track section T² is energized with current of a definite polarity, over a circuit from the (+) terminal of battery B¹, back contact 14 10 of relay NR¹, back contact 15 of relay RR¹, contact 16 of relay P¹, wires 17 and 18, through the lower rail of the track section T², wire 19, through the operating winding of relay TR², wire 20, through the upper rail of the track section T², 15 wire 21, contact 22 of relay P¹, back to the (-) terminal of battery B¹. However, when the relay P¹ operates to open contacts 16 and 22 and close contacts 23 and 24, the track section T² is de-energized for the reason that the circuit to battery B¹ is open at the parallel front contacts 25 of relay RR¹ and 26 of relay NR¹. It is then obvious that with the relays RR¹ and NR¹ both de-energized the relay P¹ is effective to apply impulses of a definite polarity (which may be 25 termed (+) impulses) to the track section T² which impulses are separated by periods of de-energization which are substantially of the same duration of time.

These time-spaced (+) impulses applied to the 30 track section T² are effective to operate contact 27 of relay TR² alternately from its right hand position as shown to its de-energized or dotted position in synchronism with the operation of the impulsive relay P¹, and during the period in 35 which the contact 27 is swung to its right hand position, or during the energized period of the track section T², an obvious circuit is completed to pick up the slow releasing relay NR². However, the characteristics of this relay NR² are 40 such that it does not drop-away during the period in which the contact 27 assumes its de-energized or dotted position, and consequently remains picked up as long as the (+) impulses continue. With the relay NR² picked up and 45 the relay RR² de-energized a circuit is completed for energizing the yellow or caution signal light 2SY at front contact 28 of relay NR² and back contact 29 of relay RR², and the red signal light 2SAR is also energized over a circuit including 50 front contact 30 of relay NR² thereby displaying a restricted-caution indication at signal 2S.

With this condition existing at the signal 2S, the track T³ is energized with time-spaced impulses in a similar manner to the track section 55 T², but these impulses are of the reverse polarity (which may be termed (-) impulses) applied thereto from battery B² over a circuit completed at front contact 31 at relay NR² and through contacts of the relay P². It is not considered 60 necessary to trace this circuit in detail by reason of its similarity to the circuit traced in describing the energization of the track section T², but it is obvious that the closing of front contact 31 of relay NR² connects the positive terminal of 65 the battery B² through the right hand set of contacts of the relay P² to the upper rail instead of through the left hand set of contacts as in the relay P¹ to the lower rail thereby causing the current flowing in the track section T³ to be in 70 the opposite direction to that flowing in the track section T².

It was previously considered that current flowing from left to right through relay TR² operated its contact 27 to the right, and consequent- 75

ly the reverse direction of current, or current flowing from right to left through relay TR^3 operates its contact 32 to the left. These time-spaced impulses of the track section T^3 are obviously effective to oscillate the contact 32 of relay TR^3 from its left hand position as shown to its de-energized or dotted position in synchronism with the operation of relay P^2 thus causing the relay RR^3 to be picked up and the relay NR^3 to be dropped, which is the reverse of the condition set up by the relay TR^2 . A circuit is thus completed to energize the yellow or caution signal light 3SY through back contact 33 of relay NR^3 and front contact 34 of relay RR^3 , and the green signal light 3SAG is energized over a circuit completed at back contact 33 of relay NR^3 and front contact 35 of relay RR^3 thereby displaying a proceed-caution indication at signal 3S which is of a lesser restriction than displayed by signal 2S by reason of the energization of the green signal 2SAG.

With this condition existing at the signal 3S, the track section T^4 is energized with impulses of a polarity such as applied to the track section T^2 which are separated or which alternate with impulses of a polarity such as applied to the track section T^3 , or that is, the energization of section T^4 is made up of alternating (+) and (-) impulses. This energization is obviously effected by the fact that the (+) terminal of battery B^3 is connected to both the left hand set of contacts of the relay P^3 by front contact 36 of relay RR^3 as well as to the right hand set of contacts by the front contact 37 of relay RR^3 .

With these impulses of alternating polarity applied to the track section T^4 , it is obvious that the relay TR^4 will operate its contact 38 from its extreme left hand position to its extreme right hand position in synchronism with the operation of the relay P^3 thereby effecting the picking up of both relays RR^4 and NR^4 . The green signal light 4SG is then energized over a circuit including front contact 39 of relay NR^4 and front contact 40 of relay RR^4 , and the red signal 4SAR is energized over a circuit including front contact 41 of relay NR^4 to thereby display a green or proceed indication at signal 4S. The track section at the left of section T^4 is likewise energized with impulses of alternating polarity inasmuch as the relay RR^4 is energized to connect the positive terminal of battery B^4 to both the right hand and the left hand sets of contacts of the relay P^4 , and consequently a signal at the left or in the rear of signal 4S will likewise display a green or proceed indication.

It is evident from the foregoing description of the operation of the system shown in Fig. 1 that a train occupying any one of the insulated track sections T is effective to shunt the associated polarized track relay TR thereby dropping both slow-releasing relays RR and RN which effects the display of the most restrictive signal indication at the entrance of that occupied section. These relays RR and RN are also effective in combination with the associated impulsive relay to apply a distinctively coded impulsive energization to the rear adjacent section which in the form shown comprises time-spaced impulses of a particular polarity, which for comparison is termed the (+) polarity.

These time-spaced (+) impulses in the section adjacent the occupied section are effective to oscillate the contact of the polarized track relay from one extreme position to center which

picks up only one of the slow releasing relays, namely relay NR , which effects the display of the next lesser restrictive indication with respect to that displayed at the entrance of the occupied section, or that is, a yellow high light limited by a red lower light. With the NR relay only picked up, an impulsive energization is applied to the section in the rear thereof, that is the second section in the rear of the occupied section, which energization comprises time-spaced impulses of the opposite polarity, termed (-) polarity.

These time-spaced (-) impulses are effective in a similar manner to oscillate the contact of the associated track relay thereby picking up the other slow releasing relay only, namely relay RR , which effects the display of a signal indication at the entrance of the second section in the rear of the occupied section which is of lesser restriction than displayed at the section adjacent the occupied section, or that is, a yellow high light modified by a green lower light. Whenever this relay RR is picked up at any section, an impulsive energization of alternating (+) and (-) polarities is applied to the rear adjacent section.

The third section in the rear of the occupied section is consequently energized with current of alternating (+) and (-) polarities which oscillates the contact of the associated track relay in a manner to pick up both slow-releasing relays NR and RR thus effecting the display of the least restrictive signal indication. In a like manner this least restrictive indication is reflected to each unoccupied section in the rear of a section having a clear signal inasmuch as the RR relays are picked up to effect the application of impulses of alternating polarities to their respective rear adjacent sections.

In Fig. 2, a modified arrangement of the present invention has been shown in which the various signal indications are obtained by effecting the application of substantially the same distinctively coded impulses to the various track sections, but the impulsive energization of any particular track section and the display of the various indications associated therewith is only effected when a train is approaching that section, thereby obviously saving unnecessary consumption of energy by the signal lights as well as unnecessary operation of both the impulsive means and the code-responsive means. In order to prepare the system for displaying signal indications to an approaching train, a polarized line circuit is employed which interconnects the adjacent track sections, and this line circuit is selectively energized from suitable split-potential batteries at each section, which batteries have been omitted from the drawings, but it is understood that (+) and (-) are opposite extreme terminals and (c) is the center or common potential thereof. A common line wire is necessary in addition to the line wires shown as connecting the track sections, which common wire has also been omitted but it is understood that it will be connected to the center tap or common of each split potential battery and to each of the terminals marked (c) in the drawings.

Additional apparatus is required in the form shown in Fig. 2 which apparatus comprises polarized line relays L (with distinctive exponents) which may be of the same type as the polarized track relays TR , slow releasing relays DR (with distinctive exponents) which repeat the de-energized position of the track relay TR , and relays G

(with distinctive exponents) which prevent the flashing of the green signal light when the restriction of the yellow indication is changing as will be more fully described later.

5 It is to be understood that the apparatus and circuits associated with each track section of the system is identical and before describing the operation of the system to prepare for an approaching train, the effect of a train occupying a particular track section will be described.

10 For example, if a train enters the track section T^6 of Fig. 2, the track circuit current will be shunted from the track relay TR^6 thereby causing its contact 46 to assume its de-energized or center position which then effects the de-energization of both relays RR^6 and NR^6 . With the relays RR^6 and NR^6 de-energized, current of a definite polarity will be applied over the line circuit to the polarized line relay associated with the forward 15 adjacent track section, or in the present case, relay L^7 . This circuit for energizing the relay L^7 may be traced from the common wire or the centered tap (c) of the associated line battery, through the windings of the relay L^7 , over line 20 wire 47, back contact 48 of relay NR^6 , wire 49, back contact 50 of relay RR^6 to (−) of the same line battery. Current flowing in this direction through the line relay L , or namely from right to left, will cause the polarized contacts thereof to 25 swing to their extreme left hand position and inasmuch as the system is symmetrically arranged it will be considered that this operation of any line relay L will occur whenever a train occupies the rear adjacent track section.

30 35 In considering the operation of the system in preparation for an approaching train, it will be considered that the apparatus shown in Fig. 2 is all assuming the definite position shown, and it will be considered that a train represented by 40 the symbol A^1 is occupying the track section T^5 . This train A^1 then effects the energization of the line relay L^6 , which is associated with the forward adjacent track section T^6 , to operate its contacts to the left as shown, all of which will be 45 obvious from the foregoing description of the energization of the similar relay L^7 during the occupancy of the track section T^6 .

50 55 With the line relay L^6 energized to swing its contacts to the left, the line relay L^7 is energized with a polarity which is the reverse of the energization of relay L^6 over a circuit from (+) of the associated line battery, through front contact 51 of relay L^6 , polar contact 52 of the same relay, wires 53 and 54, front contact 48 of relay NR^6 , line wire 47 through relay L^7 to the common wire (c) or common potential of the same line battery. This reverse polarity of energization of the relay L^7 , or that is, with current flowing from left to right through its windings, operates its polarized 60 contacts to the extreme right hand position thereby opening one energizing circuit for next forward line relay L^8 at the polar contact 55, and inasmuch as the relay RR^7 is picked up in response to a clear traffic condition, the circuit for 65 applying the reverse polarity thereto is also opened at back contact 45 of relay RR^7 .

70 75 From the above description of the line circuits of Fig. 2, it may be seen that a train entering any track section is effective to energize the line relay associated with the first forward section with a definite polarity which operates the polarized contacts of this line relay to a position which applies energy of an opposite polarity to the line relay associated with the second forward section, but this operates the polarized contacts of this sec-

ond line relay to a position which does not energize the line relay associated with the third forward section. This operation of the line circuits obviously shifts from section to section in advance of the train as it progresses throughout the system, and with such operation in mind, the means for initiating operation of the impulsing means and energization of the signal lamps will now be considered.

80 85 The energization applied to the line relay associated with the second section in advance of the occupied section, or relay L^7 , is effective to pick up the neutral contacts thereof although the polarity of such energization operates the polarized contacts to a position having the same effect 15 on the circuits which they control as during the de-energized condition of the relay. The neutral front contact 44 of relay L^7 then energizes the impulsing relay P^7 , and the rails of the rear adjacent section T^6 are connected to the oscillating 20 contacts of the relay P^7 by the respective neutral front contacts 56 and 57 of relay L^7 . The associated track battery B^7 is then connected to the contacts of relay P^7 to apply impulses of energy 25 to the section T^6 of a polarity and arrangement selected by the positions of relays RR^7 and NR^7 , all of which is accomplished in the same manner as described in connection with the embodiment shown in Fig. 1 and consequently will not be described in detail. However, considering that the 30 same code arrangement as used in Fig. 1 is employed, a code comprising alternating (+) and (−) impulses is transmitted over the section T^6 , which distinctly affects the code receiving means at the entrance of this section also in the same 35 manner as described in Fig. 1 inasmuch as the same code receiving means is employed with the exception of the added relays G and DR which do not function in this case.

40 45 With the line relay L^6 energized with a normal polarity as previously described, the code receiving means is now effective to energize the clear signal light $6SG$ over a circuit from (+), front contact 58 of relay RR^6 , front contact 59 of relay NR^6 , back contact 60 of relay G^6 , through the signal light $6SG$, polar contact 61 of relay L^6 in its left hand position, neutral front contact 62 of the same relay to (−). The lower red signal light $6SAR$ is likewise energized over an obvious circuit completed at front contact 63 of relay NR^6 thereby displaying a clear or green over red indication at signal $6S$ to the approaching train A^1 .

50 55 However, no indication is displayed at the signal associated with second section in advance of the train A^1 , or considering section T^7 , the polarized contact 64 of relay L^7 being in its extreme right hand position opens the energizing circuit for all the signal lamps at signal $7S$, and likewise no indication is displayed at succeeding 60 forward sections, or as may be seen at section T^8 the energizing circuit for all the signal lamps at signal $8S$ is opened at the neutral front contact 65 of relay L^8 which is de-energized.

65 70 The circuit for energizing the track section T^7 with the relay L^8 de-energized is shifted to exclude the contacts of the impulsing relay P^8 and this relay P^8 is de-energized by the open front contact 72. The track section T^7 is then energized with continuous current over a circuit from the (+) terminal of battery B^8 , front contact 67 of relay RR^8 , back contact 68 of relay L^8 , through the upper rail of the track section T^7 , through the windings of relay TR^7 from right to left, through the lower rail of section T^7 , back contact 69 of 75

relay L⁸, front contact 70 of relay RR⁸, to the (—) side of battery B⁸. This continuous current flowing through relay TR⁷ from right to left causes its polarized contacts to operate to their 5 extreme left hand position thereby maintaining relay RR⁷ energized.

It is then obvious that when a train is not approaching or if approaching and more than one section in the rear of any particular section of 10 the system shown in Fig. 2, the energization of that particular section is continuous rather than impulsing, and of a polarity which corresponds to the forward traffic conditions, or as may be seen by considering the energization of section 15 T⁷, the polarity is selected by contacts 66 and 71 of relay NR⁸ and contacts 67 and 70 of relay RR⁸. This means for selecting the polarity of continuous energization of a section which is not being approached by a train may be more 20 clearly understood by considering that the section T⁸ is occupied thereby shunting relay TR⁸ and dropping both relays RR⁸ and NR⁸. This condition reverses the energization of section T⁷ by the pole-changing contacts 67 and 70 of relay 25 RR⁸ de-energized, which contacts are connected to the rails of the section T⁷ through back contacts 68 and 69 of relay L⁸ de-energized, which circuit is considered to be obvious from the drawings and foregoing description and will not 30 be traced in detail. This reversed polarity shifts the polarized contacts of relay TR⁷ to the right hand position picking up relay NR⁷ and dropping relay RR⁷, but a caution indication is not displayed at singal 7S until an approaching train 35 energizes the relay P⁸ to impulse this energization and oscillate contact 43 of relay TR⁷ from the right hand position to center thereby picking up both relays NR⁷ and DR⁷. A circuit is then completed for energizing the caution signal light 40 7SY including front contact 75 of relay DR⁷, front contact 76 of relay NR⁷ and back contact 71 of relay RR⁷, and the lower red light 7SAR is energized over a circuit completed at front contact 78 of relay NR⁷.

45 The chief function of the DR relays, which are energized when the associated track relay is de-energized or oscillating from one extreme position to center, is to control the signal energizing circuits in a manner to display a most restricted 50 indication in the event that an approaching train fails to impulse the energization of the associated track section due to a failure of a line circuit or an impulsing relay. This may be specifically pointed out by considering that a train is approaching the section T⁷, but for some reason either the impulsing relay P⁸ fails to operate or the line relay L⁸ fails to connect the rails to the contacts of the impulsing relay thus substituting a caution or a Y indication for what should be 55 a clear or G indication, were it not for the DR⁷ relay. In this case the energization of the section T⁷ is continuous which picks up either relay RR⁷ or NR⁷ according to the polarity but does not pick up relay DR⁷. A circuit is then completed, due to the DR⁷ relay, for energizing the red signal light 7SAR including back contact 79 of relay DR⁷ and either back contact 80 of relay NR⁷ or back contact 81 of relay RR⁷, and the lower red light 7SAR is also energized over a similar 65 energizing circuit obvious from the drawings. Thus a failure of the clear indication, G, instead of giving a caution indication, Y, gives a stop indication, R, so as to apprise the train man that the signal system is out of order.

70 The specific function of the G relays in Fig. 2

may be described by considering the signal 2S of Fig. 1 during a condition in which its indication is changing from the yellow over red indication as shown to a yellow over green indication now shown as displayed by signal 3S. 5 In changing this indication at signal 2S, the relay RR² must be picked up and the relay NR² dropped, but as the pick-up time of these relays must be shorter than the drop-away time, there will be a period of time in which both relays 10 will be picked up and obviously energize the green signal light 2SG during such period. To obviate such a flashing of the green signal light, the relays G were added in the embodiment shown in Fig. 2 and arranged to be picked up 15 whenever either of the slow-releasing relays NR or RR is de-energized and to control the energizing circuit for the green signal lights through a back contact thereof. This arrangement in Fig. 2 obviously requires the relay G to drop 20 when both relays NR and RR are picked up before the green signal light can be energized, and the drop-away time of the relay G is arranged to be greater than the time required for the execution of the change in condition of the slow 25 releasing relays, thus holding the energizing circuit for the green signal light open during a change in the yellow indication.

An automatic block signaling system has thus been provided in which an indication of any 30 one of four different degrees of restriction is automatically displayed at the entrance of each block or section of the system, and in which such various indications are selectively displayed without the use of auxiliary line circuits inter- 35 connecting the blocks. A modified form of such a system has also been provided which enables the saving of considerable energy and needless operation of various parts by preventing the display of a signal indication and stopping the 40 oscillating operation of certain apparatus at times when a train is not approaching or occupying the section with which the particular signal and apparatus are associated.

A further feature which is inherent in the 45 present invention is the increased reliability of the operation of the track circuits. This is because the impulsing energization of the track circuits effects the alternate picking up and dropping of the track relays, and inasmuch as it 50 is well known that a larger amount of current is required to pick up than is required to hold up such relays, it follows that more reliable shunting of the track circuits will be obtained by enabling a higher resistance rail shunt to 55 prevent picking up of the oscillating track relay than would effect the dropping of a continuously energized relay.

The above rather specific description of one 60 form of the present invention is given solely by the way of example, and is not intended, in any manner whatsoever, in a limiting sense. It is also to be understood that various modifications, adaptations and alterations may be applied to meet the requirements of practice, without in any manner departing from the spirit or scope of the present invention, except as limited 65 by the appended claims.

Having thus described my invention, what I 70 claim is:—

1. In a railway signaling system, a plurality of insulated track sections, a polarized relay connected across one end of each track section, two slow releasing relays controlled by each polarized relay in a manner to distinctively respond to 75

variously coded impulses applied to the associated track section, a signal associated with each track section, control means effecting the display of indications at each of said signals in accordance with the condition of the associated slow releasing relays, an oscillating contact means connected to the other end of each track section, a source of energy associated with each track section, and means for selectively connecting each source of energy to the contacts of the associated oscillating contact means in a manner to form said variously coded impulses in accordance with the position of the slow releasing relays associated with one adjacent track section.

2. In a railway signaling system, an insulated track section, a forward adjacent track section and a rear adjacent track section, means for selectively applying impulses of one polarity, of a different polarity or of alternating polarities to one end of said insulated track section in accordance with the traffic condition of said forward track section, a polarized relay connected to the other end of said insulated track section and responsive to each of said impulses applied to the track section, signal control relays selectively energized by the polarized relay, and means for selectively applying impulses of one polarity, of a different polarity or of alternating polarities to said rear adjacent track section in accordance with the condition of said signal control relays.

3. In a railway signaling system, an insulated track section with at least three forward track sections and a rear adjacent track section, a first source of direct current energy, a means for applying impulses generated from said first source of energy to one end of said insulated track section which are selected by differing polarity and sequence to form any one of three distinctive codes in accordance with the location of a train in said three forward track sections, a signal control means connected to the other end of said insulated track section which signal control is distinctively responsive to said distinctive codes, a second source of direct current energy, and a means for applying impulses generated from said second source of energy to said rear adjacent track section which are distinctively coded in accordance with the condition of said signal control means.

4. In a railway signaling system, a plurality of insulated track sections, a wayside signal associated with each section, signal control means for each section for effecting the display of a most restrictive indication at said signals when a train occupies the associated section, means including the signal control means arranged to apply time-spaced impulses of one polarity to the first section in the rear of a section occupied by a train, means including the signal control means arranged to apply time-spaced impulses of another polarity to the second section in the rear of a section occupied by a train, the signal control means at each section being arranged to distinctively respond to each of said time-spaced impulses, and means including the signal control means arranged to apply impulses of alternating polarities to the third section in the rear of a section occupied by a train, whereby said signal control means distinctly responds to each of said impulses of alternating polarities.

5. In a railway signaling system, a plurality of track sections, means normally energizing each of said sections with continuous current, means

for impulsing the continuous current of said sections upon the approach of a train, code selecting means at each section arranged to select the polarity and arrangement of said impulsing energy to form any one of three distinctive codes in accordance with forward traffic conditions, and code responsive means at each section operable to distinctively respond to the coded impulses of the associated section. 5

6. In a railway signaling system, a plurality of track sections, means normally energizing each of said sections with continuous current, means for impulsing the continuous current of said sections upon the approach of a train, code selecting means at each section arranged to select the 15 polarity and arrangement of said impulsing energy to form any one of three distinctive codes in accordance with forward traffic conditions, code responsive means at each section operable to distinctively respond to the coded impulses of the 20 associated section, wayside signals at each section arranged to display various indications to an approaching train in accordance with the condition of the associated code responsive means, and means for preventing the display of signal 25 indications when a train is not approaching the associated section.

7. In a railway signaling system, two adjacent insulated track sections, an oscillating contact means operable to actuate contacts in substantially equal time-spaced oscillations, a source of energy, two slow releasing relays having code selecting contacts arranged to connect said source of energy through said oscillating contacts to one end of one of said track sections whereby time-spaced impulses of either one polarity or of another polarity or impulses of alternating polarities are selectively applied thereto, a polarized relay connected to one end of the other track section and responsive to code impulses, one of the 40 slow-releasing relays being picked up during one polarity of impulsing energization of said polarized relay, and the other slow-releasing relay being picked up during another polarity of impulsing energization of said polarized relay, the 45 slow-releasing relays being arranged to both pick up during alternate polarities of energization of said polarized relay. 30 35 40 45

8. In a railway signaling system including a plurality of track sections each selectively energized by impulses coded in accordance with the respective forward traffic conditions, a polarized relay at each track section arranged to distinctly respond to said coded impulses, two slow releasing relays associated with each of said polarized 55 relays and connected in a manner to select various circuits in accordance with the coded impulses applied to the associated polarized relay, signal means arranged to display a clear or any one of a plurality of more restrictive indications 60 in accordance with the circuit selected by the associated slow releasing relays, and means for preventing a momentary display of a clear indication on changing from one to another of the more restrictive indications. 65

9. In a railway signaling system, a plurality of track sections, energizing means for each track section, wayside signals associated with each track section, a polarized line relay associated with each track section, a circuit for energizing said 70 line relay with current of one polarity when a train occupies a rear adjacent track section and with current of another polarity when a train occupies a second rear track section, means effective when said line relay is energized with cur- 75 75

rent of either polarity to impulse the energization of the track section next in the rear, and means permitting said signals to display an indication only when the associated line relay is energized with current of one polarity.

5 10. In a railway signaling system, a plurality of track sections, energizing means for each track section, wayside signals associated with each track section, a polarized line relay associated with each track section, a circuit for energizing said line relay with current of one polarity when a train occupies a rear adjacent track section and with current of another polarity when a train occupies a second rear track section, means effective when said line relay is energized with current of either polarity to impulse the energization of the track section next in the rear, means permitting said signals to display an indication only when the associated line relay is energized with current of one polarity, and means effecting the display of a most restrictive indication at said signals when the associated line relay is energized with current of said one polarity but the energization of the associated track section is not impulsing.

20 11. In a railway signaling system, a first track section, a rear and a forward track section adjacent thereto, a polarized line relay associated with each of said track sections, a wayside signal associated with each of said track sections, a circuit arranged to apply one polarity of energy to the line relay associated with said first track section when a train occupies said rear adjacent track section, a circuit arranged to apply another polarity of energy to the line relay associated with said forward adjacent track section when the line relay associated with said first track section is energized with said one polarity, means for applying coded impulses to each of said track sections when the line relay associated with the section next in advance is energized with either of said polarities, and means for displaying a signal indication by said wayside signals only when the associated line relay is energized with 25 said one polarity.

40 12. In a railway signaling system, a plurality of track sections, a polarized relay connected across one end of each track section, two slow releasing signal control relays controlled by each of the polarized relays, a continuous current source of energy, and means for selectively applying interrupted current from the source of energy of one polarity, a different polarity or of alternating polarities to the other end of each track section in accordance with the energization of the associated signal control relays, said current being interrupted at a frequency whereby the associated polar relay can operate substantially in synchronism therewith.

45 60 13. In a railway signaling system, a plurality

of insulated track sections, means for each section for applying time-spaced impulses of one polarity to its track section during a first traffic condition, for applying time-spaced impulses of another polarity to its track section during a second traffic condition, for applying impulses of alternating polarities to its track section during a third traffic condition, each means including wayside oscillating means distinctively responsive to each impulse applied by the means of the track section next in advance thereof and connected to its track circuit whereby to distinctively respond to each of said arrangements of impulses applied by the means next in advance in a manner to selectively display various signal indications.

5 10 14. In a railway signaling system, a plurality of insulated track sections, means for each section for generating time-spaced impulses of one polarity in its track section during a first traffic condition, for generating time-spaced impulses of another polarity in its track section during a second traffic condition, for generating impulses of alternating polarities in its track section during a third traffic condition, and wayside means included in the generating means, connected to its track section which distinctively respond to each of said arrangements of generated impulses generated by the means of the track section next in advance in a manner to selectively display various signal indications.

20 25 30 35 40 45 50 55 60 15. In a coded track circuit system for railroads; a plurality of track circuit sections; a coding device for each track circuit section for controlling the supply of coded rail current to the rails at the exit end of that section; approach control relay means at the exit end of each section and operable over a traffic controlled line circuit by a current of any one of a predetermined number of distinctive characters including a current of a last distinctive character; means controlled by each except the last of said control relay means, when energized by current except current of the last of the distinctive characters, for controlling the supply of current to the approach control relay means for the track section next in advance; each control relay means when energized by current of one of said distinctive characters, except when energized by current of said last character, operating to energize the next control relay means by current of a different distinctive character; and means governed by each of said control relay means when energized for controlling the operation of the associated coding devices; whereby said coding devices are normally inactive while no train is present in said plurality of track sections and are automatically set into operation for a predetermined number of track sections ahead of an occupied track section.
